UNITED STATES PATENT OFFICE

157,546

TIE RACK OR SIMILAR ARTICLE

Frank J. Trabert, Los Angeles, Calif.

Application August 9, 1948, Serial No. 147,996

Term of patent 14 years

(Cl. D33—8)

To all whom it may concern:

Be it known that I, Frank J. Trabert, a citizen of the United States, residing in Los Angeles, in the county of Los Angeles, State of California, have invented a new, original, and ornamental Design for a Tie Rack or Similar Article, of which the following is a specification, reference being had to the accompanying drawing, forming a part thereof.

Figure 1 is a plan view of a tie rack embodying my new and novel design.

Figure 2 is a side view of the tie rack shown in Figure 1.

Figure 3 is an end view of the tie rack shown in Figure 1.

Figure 4 is a sectional view taken on line 4—4 of Figure 2.

I claim:

The ornamental design for a tie rack or similar article, as shown.

FRANK J. TRABERT.
